FLASH LAMP

Lewis V. McCarty, Cleveland Heights, Ohio, assignor to
General Electric Company, a corporation of New York
Filed Apr. 4, 1961, Ser. No. 100,578
2 Claims. (Cl. 67—31)

This invention relates in general to flash lamps of the type comprising a sealed radiation transmitting envelope containing a quantity of combustible light producing material and a combustion supporting medium such as an oxygenous gas which enters into a reaction with the combustible material with the resulting emission of an instantaneous flash of actinic light of high intensity. More particularly, this invention relates to a flash lamp containing the combustible material, cyanogen gas, which with oxygen, reacts to provide the source of actinic light.

The combustible material used in present-day commercial flash lamps is a magnesium, aluminum or zirconium alloy foil or filament. The most objectional feature of a lamp of this type for use in color photography is that the spectral distribution of the light emitted is very dissimilar from ordinary sunlight. Thus, the lamp must either be equipped with a filter coating or used with special film. However, prior to this invention, the only practical lamps were based on metal foils, filaments or powders which radiated sufficient light for photographic purposes because of the liquid droplets of metal oxide formed in the high temperature reaction. While flash lamps have been customarily made with a foil or filament filling because of good radiating efficiency some work has been done previously towards developing a gas filled flash lamp. For example, the Van Liempt et al., Patent No. 2,013,371, discloses the use of several combustible gas mixtures for use in flash lamps. However, such lamps have not hitherto been practical mainly because of low light output, when used as previously disclosed, because most hot gases are relatively poor radiators of light as compared with the liquid droplets of metal formed in the actinic reaction of a metal foil or filament with a gas, and also because of poor storage life during which the reactant materials may attack the lead-in wires. The aforesaid deficiencies are overcome by a flash lamp constructed in accordance with the instant invention.

An object of this invention, therefore, is to provide a flash lamp containing a gaseous combustible mixture including certain ratios of cyanogen and oxygen wherein excited particles of the gaseous mixture act as efficient radiators of light comparable to the solid or liquid particles present in the combustible material filled flash lamps.

Since flash lamps are made for only a single use and thereafter must be thrown away, another object of this invention is to provide such a flash lamp which is practical and economical to produce.

Still another object of this invention is to provide a flash lamp having a short duration of light output and emitting light having a spectral distribution comparable to outdoor light on a sunny day.

In accordance with the above-mentioned objects this invention relates to a flash lamp comprising a sealed glass bulb filled with a combustible mixture of cyanogen and oxygen, the cyanogen-oxygen ratio being in the range between 1 and 1.4 together with means for igniting said mixture.

Further objects and advantages of the invention will appear from the following detailed description of the invention and from the accompanying drawing.

In the drawing, FIG. 1 is a view in elevation of a flash lamp comprising the invention and FIG. 2 is a graph showing the effects of varying the cyanogen-oxygen ratio on the light intensity.

2

Referring to the drawing, a flash lamp according to the invention comprises a sealed glass envelope 4 cemented to a metal base 5. Ignition means 6 for igniting the combustible gas filling comprises lead wires 8, 9 electrically connected to base 5 and its associated center contact 5' together with a filament 10 connected across lead wires 8, 9. The combustible gas is readily ignitable at the temperature attained by the filament 10, hence primer material, such as used in present-day commercial lamps, is not necessary for ignition purposes. However, primer beads 11 may be provided so as to control the time of ignition. Primer beads 11 may consist of a mixture of zirconium, potassium perchlorate and magnesium bonded together with a suitable binder such as 2 to 5% solution of nitrocellulose in amy1 acetate.

The combustible gas mixture comprises cyanogen and oxygen reacting generally in the following manner:

If sufficient oxygen is furnished, the mixture will also react as follows:

While Reaction 2 releases more energy than Reaction 1 since in reality it involves further oxidation of carbon monoxide which is produced according to the Reaction 1, it might be believed that stoichiometric mixtures for producing the Reaction 2 would produce the most light. However, in spite of the lesser amount of energy released, it has been found that Reaction 1 radiates more light. This unusual result will be observed from an inspection of the data given below and shown graphically in FIG. 2 of the drawing. This phenomenon may be explained by the great stability of the carbon monoxide molecules produced by Reaction 1 which results in a higher reaction temperature. Whatever the explanation, Reaction 1 is found to radiate approximately ten times as much light as Reaction 2. A further increase in light emission occurs on going to the cyanogen rich mixtures and the optimum mixture of about 47% oxygen and 53% cyanogen radiates approximately forty-seven times as much light as the stoichiometry for Reaction 2 as shown in the following table:

Light Emission Data for $\text{C}_2\text{N}_2/\text{O}_2$ Reaction

	C_2N_2 Press., mm.	O_2 Press., mm.	Percent, C_2N_2	Percent, O_2	Ratio, $\text{C}_2\text{N}_2/\text{O}_2$	Lumens at Peak
50	201.7	154.2	56.7	43.3	1.308	270,000
	201.6	163.6	55.2	44.8	1.232	400,000
	201.8	174.2	53.7	46.3	1.158	470,000
	201.5	184.4	52.2	47.8	1.093	390,000
	201.2	194.6	50.8	49.2	1.034	250,000
	200.6	211.4	48.7	51.3	0.949	50,000
	201.2	248.9	44.7	55.3	0.808	20,000

	201.1	399.0	33.5	66.5	0.504	10,000
	201.4	550.7	26.8	73.2	0.366	10,000
	250.3	194.2	56.3	43.7	1.289	400,000
	250.6	203.7	55.2	44.8	1.230	490,000
	250.4	215.5	53.7	46.3	1.162	550,000
	250.6	225.7	52.6	47.3	1.110	600,000
	250.3	236.9	51.4	48.6	1.057	500,000
	250.7	247.6	50.3	49.7	1.013	270,000
	301.2	259.9	53.7	46.3	1.159	670,000
	301.2	269.7	52.8	47.2	1.117	740,000
	300.9	280.3	51.8	48.2	1.073	690,000
	351.8	309.4	53.2	46.8	1.137	810,000
65	351.8	319.1	52.4	47.6	1.102	840,000
	351.8	328.4	51.7	48.3	1.071	810,000

This data is represented graphically in FIG. 2 of the drawing. As shown in curve 13, the light emitted from the cyanogen-oxygen mixture increases greatly at a ratio of approximately 1.4 and the light intensity further increases as the ratio approaches approximately 1.15. Then at the stoichiometry of Reaction 1 noted above, that is,

as a cyanogen-oxygen ratio of 1.0 is approached, the light intensity is approximately $\frac{1}{2}$ of intensity of the optimum mixture. When sufficient oxygen is provided for the stoichiometry of Reaction 2, that is, where the cyanogen-oxygen ratio is .5 the light intensity is approximately $\frac{1}{47}$ of the light output from the optimum mixture, that is, where the cyanogen-oxygen ratio is approximately 1.15. Curves 14, 15 and 16 show the same optimum mixture to be necessary as additional amounts of combustible gas are added by increasing the filling pressure of the mixture in the glass envelope 4. The light intensity of the optimum mixture would appear to be relatively independent of the total pressure within the bulb, and is only dependent on the provision of an excess of cyanogen gas molecules which are excited by the reaction to radiate light.

The burned lamps have a carbon residue in them, and it is believed that a part of the excess cyanogen decomposes to form carbon. Carbon vapor as such or as cyanogen radicals in the presence of excessive nitrogen at the high temperatures produced by the reaction act as a radiating gas performing a function similar to the molten droplets in a conventional metal foil or filament flash lamp. The addition of other carbon vapor producing gases, such as benzene and acetylene, to a mixture containing equal amounts of cyanogen and oxygen lends some support to this belief since improved light emission results. The effect of selected foreign gases which produce radicals subject to being excited is as follows:

*Effect of Foreign Gases on the Light Emission
of the C_2N_2/O_2 Reaction*

Mm: Added Gas	C_2N_2 Press., mm.	O_2 Press. mm.,	Peak Light Intensity Lumens
Acetylene:			
0.0-----	302.6	300.5	240,000
7.9-----	302.3	300.2	370,000
13.7-----	302.8	299.6	540,000
17.9-----	303.1	299.3	570,000
35.5-----	302.8	299.5	520,000
55.8-----	303.1	300.2	450,000
Benzene:			
2.0-----	302.6	299.6	470,000
4.1-----	302.1	300.3	500,000
6.2-----	302.1	300.1	600,000
8.9-----	302.0	299.4	500,000
12.2-----	302.3	300.3	500,000
18.1-----	302.5	300.0	350,000
24.0-----	300.3	299.2	240,000

As will be noted, the effect of these carbon vapor producing gases influence light emission similarly to the manner of excess cyanogen but not to as large an extent. The chief difference seems to be that the hydrogen produced at flame temperature of the reaction is dissociated while the nitrogen which is produced from the pure cyanogen-oxygen reaction is largely combined as molecular nitrogen. Since large amounts of energy are needed to dissociate hydrogen the maximum flame temperature drops and the optimum mixture is not as good a radiator as mixtures containing simply excess cyanogen.

An important advantage of a flash lamp comprising this invention is the color balance of the cyanogen-oxygen flash. The spectra of the flashes show cyanogen bands beginning at 4606, 4216 and 3883 angstroms and swan bands for the C_2 molecule at 5635, 5165, 4737 and 4382 angstroms and a relatively rich but less intense spectrum at longer wavelengths. While this appears to be a rather banded structure, colored photographs have been made using ordinary outdoor color film with cyanogen-oxygen flashes as the sole source of illumination with very satisfactory results.

Although a preferred embodiment of my invention has been disclosed, it will be understood that the invention is not to be limited to the specific construction and arrangement of parts shown and that they may be widely modified within the spirit and scope of this invention as defined by the appended claims.

What I claim as new and desire to secure by Letters

30 Patent of the United States is:

1. A flash lamp comprising a sealed envelope containing a gaseous combustible mixture of cyanogen and oxygen wherein the cyanogen-oxygen ratio is between 1 and 1.4.
2. A flash lamp comprising a sealed envelope containing a gaseous combustible mixture of cyanogen and oxygen wherein the cyanogen-oxygen ratio is approximately 1.15.
